DESIGN FOR A REFRIGERATOR CABINET

Harold Van Doren, Ardmore, and Leo J. Amore,
Philadelphia, Pa., assignors to Philco Corpora-
tion, Philadelphia Pa., a corporation of Penn-
sylvania

Application April 2, 1948, Serial No. 145,504

Term of patent 3½ years

(Cl. D67—3)

To all whom it may concern:

Be it known that we, Harold Van Doren and Leo J. Amore, citizens of the United States, residing, respectively, at Ardmore, in the county of Montgomery and State of Pennsylvania, and at Philadelphia, in the county of Philadelphia and State of Pennsylvania, have invented a new, original, and ornamental Design for a Refrigerator Cabinet, of which the following is a specification, reference being had to the accompanying drawing, forming part thereof, in which:

Figure 1 is a view, in perspective, of a refrigerator cabinet in open position, showing our new design;

Figure 2 is a fragmentary sectional view, taken along the line 2—2 of Figure 1; and

Figure 3 is a fragmentary sectional view taken along the line 3—3 of Figure 1.

The side of the cabinet not disclosed in the drawing is substantially plain and similar to the side shown.

The dominant features of our design reside in the portions shown in full lines.

We claim:

The ornamental design for a refrigerator cabinet, substantially as shown and described.

HAROLD VAN DOREN.
LEO J. AMORE.
